UNITED STATES PATENT OFFICE.

STUART B. MOORE, OF LA PORTE, TEXAS.

ROAD STRUCTURE.

Application filed August 27, 1925. Serial No. 52,800.

The object of my invention is a road structure which combines, to a greater extent than hitherto possible, the elements of durability and economy.

5 Experiments with which I have been connected, show that over 97% of vehicular traffic will keep to a defined trackway—if there are ruts in the road, for instance, this percentage of traffic will keep in them. Further 10 experiments have convinced me that the road base must be separated from the surface by a definite line of demarcation in order that it may be protected from vibration and its construction thus rendered less costly.

15 My invention consists, consequently, in the provision of means tending to keep traffic in a definite trackway, means rendering this trackway particularly durable and, in case of need, easily renewable, and a base beneath 20 the trackway and separate therefrom, the whole road surface being of water proof construction.

In the drawings, Fig. 1 shows, in cross section, a road embodying the principles of the 25 present invention, and

Fig. 2 shows a top plan view of a short stretch of such a road.

Referring to the drawings, Fig. 1 in particular, 10 represents an invisible trackway comprising, preferably, concrete members reinforced with longitudinal steel strips 11 and tie members 12. The rails 10 are of course spaced in accordance with standard vehicle gauge, and they have, preferably, a flat top 30 surface. A cushioning layer 13, of sand, mortar, or the like, is spread on the upper surface of the rails 10, and on top of this layer the treadways 14 are laid. These treadways consist preferably of especially durable 35 blocks, or inserts, which may be of stone, brick, or any similar material, but I do not include in this category concrete blocks, since these are not sufficiently wear-resistant and do not form a good permanent bond with the 40 asphalt. If concrete blocks were used, the asphalt would soon be drawn away from them, forming cracks and destroying the 45

waterproof character of the surface. The interstices of the durable block treadways are plugged with asphalt, or the inserts may be 50 grouted in with cement. In any event, it is important that the blocks or inserts form a water proof surface.

Intermediate the rails 10 is a filling 15 of compacted gravel, crushed stone, or other 55 suitable material, having a definite camber, as shown. This filling, at its edges, extends about to the lower edges of the treadways 14, and a layer 16 of compacted rock asphalt covers the filling, forming a water proof 60 surface therefor and a water proof bond with the treadways 14. At either side of rails 10 is a filling 17 of compacted road metal covered with a layer 18 of compacted rock asphalt bonding with treadways 14. 65

The asphalt layers 16 and 18 may, indeed, meet over the treadways 14; in such case, however, the layer will soon wear down so that the durable inserts are exposed and take the wear. When the inserts become 70 badly worn, they can be easily removed, even one at a time, and replaced by new ones. These inserts will receive nearly all the wear since the cambered intermediate section 16 will tend to keep traffic on them. The 75 rails 10 are shielded in a great degree from vibration stresses by the cushion and their size may be considerably reduced below what would ordinarily be considered appropriate.

A road such as described can be constructed very economically and will give excellent wear. Again, the wearing surfaces, which are of relatively small extent, may be readily renewed and small expense.

Having thus described my invention I 85 claim:

A road comprising a base having reinforcing trackways wholly submerged therein, a relatively thin surface of bituminous material, and durable inserts bonded in said surface directly above said trackways. 90

The foregoing specification signed at Temple, Texas, this 29th day of July, 1925.

STUART B. MOORE.
